UNITED STATES PATENT OFFICE.

SYDNEY WOODROFFE PASCALL, OF LONDON, ENGLAND.

AIR-TIGHT COVER FOR JARS AND BOTTLES.

1,138,308.

Specification of Letters Patent.

Patented May 4, 1915.

Application filed March 26, 1914. Serial No. 827,294.

To all whom it may concern:

Be it known that I, SYDNEY WOODROFFE PASCALL, a subject of the King of Great Britain, residing at London, England, have 5 invented certain new and useful Improvements in Air-Tight Covers for Jars and Bottles, of which the following is a full, clear, and exact description.

The object of this invention is to produce 10 air tight covers for jars and bottles in an economical way. For this purpose I employ a thin metal disk between the screw cap and the cork disk in a manner I shall now describe with the aid of the accompanying 15 drawings, wherein—

Figure 1 is a vertical section of the outer cap forming part of my invention; Fig. 2 is a vertical section of the thin, circular metallic disk which I employ; Fig. 3 is a vertical section of the cork disk, and Fig. 4 is a section taken across the top of a jar, showing my improved cover assembled thereupon.

Referring to the drawings, the cap, which 25 is indicated by *a*, is of the ordinary construction except that it is concaved throughout the entire area of its top portion, while the disk or stretcher *b*, which is made of thin metal of slightly less diameter than cap *a*, is concaved throughout the major portion of its central area, though its concavity is preferably not as deep as that in the cap. The sealing disk, which is indicated by *c*, may be of cork or other pliable material and is of 30 sufficient area to cover the mouth of the bottle or jar which is indicated by *d*.

In assembling my improved cover, the disk *c* is placed across the mouth of the jar, the metallic disk *b* with its concave surface 40 facing upwardly, is placed on top of disk *c* and the cap *a* is screwed down upon the neck of the jar in the usual manner, the convex surface of the cap engaging the concave surface of the metallic disk, while the 45 latter stretches the cork disk across the

mouth of the bottle or jar and at the same time compresses the outer edge of the cork on the top of the bottle.

It will be noted that the concavity of the outer cap *a* is somewhat deeper than that 50 of the slightly concaved disk *b* so that the said disk is primarily engaged in the center by the depression of the lid *a*. By means of the central pressure applied as above stated the cork disk is subjected all around its edge 55 to an even pressure which insures the desired contact between said cork and the bottle.

I claim:—

1. In combination with a jar or other receptacle having a relatively large mouth threaded exteriorly, a closure therefor comprising a cover having a threaded flange for securing it over the mouth of the receptacle and a centrally dished portion, a disk of 65 flexible material positioned on the top and over the mouth of said receptacle, and a centrally dished metallic disk interposed between the flexible disk and the cover, the dished portions of said cover and last 70 named dish engaging each other when said cover is screwed down over the mouth of the receptacle.

2. A closure for jars or other receptacles having a relatively large mouth comprising 75 an outer dished cover having a threaded flange for connecting it to the receptacle, a cork disk upon the end of the receptacle a dished disk interposed between said cork disk and the said cover, said disk having its 80 dishing somewhat shallower than the dishing of the cover whereby the said cover primarily engages said disk in the center.

In testimony whereof I have affixed my signature in presence of two witnesses.

SYDNEY WOODROFFE PASCALL.
